(57) **CLAIM**

The ornamental design for a beverage machine, as shown and described.

DESCRIPTION

FIG. 1 is a top, front, left side perspective view of a beverage machine showing a first embodiment of our new design;
FIG. 2 is a left side elevation view thereof;
FIG. 3 is a front elevation view thereof;
FIG. 4 is a right side elevation view thereof;
FIG. 5 is a rear elevation view thereof;
FIG. 6 is a top plan view thereof;
FIG. 7 is a bottom plan view thereof;
FIG. 8 is a top, front, right side perspective view thereof;
FIG. 9 is a top, front, right side perspective view of a beverage machine showing a second embodiment of our new design;
FIG. 10 is a left side elevation view thereof;
FIG. 11 is a front elevation view thereof;
FIG. 12 is a right side elevation view thereof;
FIG. 13 is a rear elevation view thereof;
FIG. 14 is a top plan view thereof;
FIG. 15 is a bottom plan view thereof; and,
FIG. 16 is a top, front, left side perspective view thereof.
The broken lines illustrate portions of the beverage machine that form no part of the claimed design.
